[57] CLAIM

The ornamental design for a rear dump refuse compactor, as shown.

DESCRIPTION

FIG. 1 is a top plan view of a rear dump refuse compactor showing my new design;

FIG. 2 is a side elevational view thereof;

FIG. 3 is a side elevational view thereof opposite to that shown in FIG. 2;

FIG. 4 is a front elevational view thereof; and

FIG. 5 is a rear elevational view thereof.
